UNITED STATES PATENT OFFICE.

CHARLES F. LANTRY, OF NEW YORK, N. Y.

MACHINE FOR ATTACHING POSTAGE-STAMPS.

SPECIFICATION forming part of Letters Patent No. 518,612, dated April 24, 1894.

Application filed May 6, 1893. Serial No. 473,197. (No model.)

To all whom it may concern:

Be it known that I, CHARLES F. LANTRY, a citizen of the United States, and a resident of New York city, in the county of New York 5 and State of New York, have invented certain new and useful Improvements in Machines for Attaching Postage-Stamps, of which the following is a specification.

My invention relates to devices for attaching postage stamps to envelopes, parcels and the like; and the object of my invention is to attach the stamps securely and rapidly by a single pressure of one hand upon a sliding piston or receptacle forming part of my machine, while with the other hand a letter or envelope is fed to the machine as soon as the preceding letter has been automatically removed from it. I accomplish this object by a machine illustrated in the accompanying 15 drawings, in which—

Figure 1 represents a longitudinal section of the machine. Fig. 2 is a plan view thereof partially in section. Fig. 3. is a transverse section through the same. Fig. 4. is a detailed view, showing the piston on its return trip and the spring-lock closed. Fig. 5 is an enlarged vertical section through the bottom part of the stamp-box G showing corner stops. Fig. 6. is a rear view of the machine 20 partially in section (cutting off the bracket A'). Fig. 7. is a perspective view of the brush-lever and its connections.

My machine consists of three distinct mechanisms, one for holding the letter to be provided with a postage stamp, one, to moisten the place on the envelope at which the stamp is to be attached, and one for carrying and successively feeding the postage stamps to be attached. All of these mechanisms are mounted 25 upon a ground plate A, carrying above a stanchion or bracket A', and below preferably a clamp A²; by means of which the machine can be secured upon the top plate of an ordinary table. At a distance above the 30 ground, plate A is mounted a narrow flanged table B and guided in a horizontal position preferably by two bolts b secured thereon and projecting below and passing through openings in the ground plate, and two springs b' 35 encircling said bolts between the bottom of the table and the top of the ground plate, and held at the required tension by the nuts

b² secured upon the screw-threaded ends of the bolts b under the ground plate. The width of the table should slightly exceed the 55 length of the postage stamp and its length is selected preferably equal to that of the smallest letter to be posted. The table B will thus form an elastic cushion when struck from above. 60

At one side preferably the left side of the machine, and partially projecting above the table B is mounted a water trough D carrying at one end a goose neck-shaped mouth-piece D'. Into this trough and through the 65 mouth-piece D' and slightly projecting beyond the mouth of the latter, is placed a wick E for carrying a moderate quantity of water to the moistening brush F³ described herein-after. 70

One end of a spring or clamp C is secured preferably to the trough D in front of the table, as shown in Figs. 3 and 4. The clamp C passes then backward and downward, and, after touching the table in the rear, passes 75 beyond it through an opening in its upright flange b³, and then upward to a connection with one end of a horizontal lever C', which is centrally mounted upon a stud C² projecting from the bracket A' (the former serving 80 at the same time as a support of one end of the trough D by means of a bracket d projecting therefrom), as shown in Figs. 6, 1, 2, and 3.

The postage stamps S are preferably arranged in a removable box G in layers of one hundred or more, with the gum sides pointing downward when the box is placed in position for work, in the sliding frame H which is guided to slide vertically upward and downward by a suitable guide frame I secured to a flange A³ projecting from the bracket A'. 85

The sliding frame H, Figs. 1, 2, and 3, is open below and provided with a cover H' having a spring lock u and hand button above, 95 and a recess H² to receive the enlarged head G' of the stamp box G which is slid into and through the frame H from above, and secured firmly therein by closing the cover H'. A slot h' in the frame H engaging with a pin i secured in the guide-frame I limits the height of the sliding motion of the frame H which is held against the pin i in its highest position, by means of a spring J one end of which 100

is secured upon the pin j mounted upon the bracket A' while the other is secured to the upper part of frame H . In a socket I' in the guide frame I is mounted rotatably the shaft 5 f provided with the cam-lever f' at one end and with the bent lever f^2 carrying the brush F^3 at the other end. A spring f^4 holds the lever f^2 against the adjustable stop f^5 and the brush F^3 against the wick E ; when the 10 stamp box is at rest in its highest position, while the cam-lever f' is resting in a horizontal position in close proximity below a sliding rail h of the sliding frame H .

The stamp box G is open below with exception of projections to support the last stamp and prevent it from premature discharge. In the drawings I show four triangular pieces mounted one at each corner of the lower opening but reserve the use of two 20 strips secured at two opposite sides or three or more prismatic or cylindrical obstructions distributed at various places along the inner edges of the lower opening of the box G , for the above named purpose. On top of the 25 layer of stamps is preferably placed a prismatic follower or weight w cut away or beveled at its bottom edges, to provide ample space for the last stamp to slide out between the weight and the retaining strips when af- 30 fixed to an envelope. The follower is held in close contact with the layer of stamps by a spiral-spring v , thus causing the stamps to bulge out slightly and the first stamp to project beyond the lower edges of the strip g and 35 thus to adhere to the moistened portion of the envelope when brought in contact therewith by depressing the sliding frame H .

The machine having been supplied with stamps and secured at the edge of a table 40 and its trough supplied with water a receiving basket having been placed on the floor in front of it and a quantity of letters placed within reach of the operator, preferably at its left, he commences by feeding a letter with 45 his left hand upon the table B and under the clamp C till it touches the flange b^3 and is firmly held in this position between the table and the clamp. While then depressing the sliding frame H carrying the stamp box G 50 one of the slide rails h will engage with the lever f' , depressing it at first, and then, sliding past it will hold it in the changed position, shown in dotted lines in Fig. 1, till the sliding frame passes the end of the lever f' 55 on its return trip, when it will be returned to its starting position by the aid of the spring f^4 , lever f^2 , and shaft f . In Fig. 6 the sliding rail h , which actuates the brush movement, and the brush-lever are shown in full view in 60 its starting position, and the descent of the rail, the corresponding position of the brush-lever and its connection, and the end position of the lever C^2 are shown in dotted lines. This motion of the lever f' , will be communicated to the brush F^3 , through the shaft f and lever f^2 and would cause the elastic ends of 65 the brush to describe an arc m shown in dotted

lines of Fig. 1, of the drawings, if the table B would not interrupt this motion and compel the moistened brush to slide over one 70 corner of the letter L placed upon the table at that portion of it which lays directly under the stamp box G and to moisten the envelope. For the remainder of the down stroke and the larger part of the return movement 75 of H and G the moistening brush F^3 will remain in a position shown in dotted lines in Fig. 1, thus allowing the box G to pass and will be returned only at the end of the up stroke of the sliding frame H to its primary 80 position, against the wick E and there receive additional moisture for moistening the next envelope. To release the stamped letter two levers C' and n are centrally mounted in such positions that one end of the lever C' is depressed by the same rail h on the sliding frame H which actuates the lever f' , at or near the moment when the box G carrying the stamps touches the letter L and the other end is raised together with the clamp 90 C to a position shown in Figs. 4 and 6. A spring n' at this moment will cause the nose n^3 of the lever n centrally pivoted at n^2 to slide over the depressed arm of the lever C' , holding the spring C in a raised position and 95 giving the stamped letter time to drop from the table into the basket. At the end of the return movement of the frame H a pin h^6 secured thereon engaging with the cam n^4 on the lever n will oscillate the lever n and release the lever C' , thus returning the clamp c' to its primary position. On the end of the 100 down stroke of the box G the spring and weight, or either one alone, will press the lowest stamp with its gummed side against 105 the moistened portion of the underlying envelope and affix the same to it and allow its removal during the recoil movement following the stroke from under the supporting strips g which to facilitate the escape are 110 preferably rounded or slanting downward. The recoil motion of the weight can be aided by a separate spring being placed under the separated hand-button between it and the cover H' , and connecting the weight w with 115 the hand-button by a rod passing through an opening in the top of the box G and the cover H' , or a heavier weight w and a recoil spring balancing the latter may alone be employed, omitting the spring v entirely. The 120 dropping of the letter from the table B will be aided by a slight jerk caused by the nuts b^2 striking against the lower face of the ground plate A .

Clamp A^2 is not an essential feature of my 125 machine but can be omitted by increasing the size and shape of the ground plate A so as to enable it to support the parts and to retain a given position when in use.

It is evident that the stamps could be inserted directly into the plunger H through suitable openings and the latter closed and the retaining strips could be attached to the open bottom of said plunger thus omitting the 130

separate receptacle G, without materially disturbing the usefulness of the machine.

Having thus described my invention, what I claim is—

- 5 1. In a machine for attaching postage stamps, the combination of an upright plunger mounted in a suitable frame and carrying a removable stamp receptacle with a cushioned table, a retaining clamp, an oscillating brush, and a water-tank as and for the purposes herein shown and described.
- 10 2. In a machine for attaching postage stamps the combination of an upright plun-

ger carrying the stamps and mounted in a suitable frame with a cushioned table, a retaining clamp, an oscillating brush, and a water-tank as and for the purposes herein shown and described.

Signed at New York, in the county of New York and State of New York, this 3d day of 20 May, A. D. 1893.

CHARLES F. LANTRY.
